REMOTE CONTROL SYSTEM

Lloyd V. Lewis, Pittsburgh, Pa., assignor to The
Union Switch & Signal Company, Swissvale,
Pa., a corporation of Pennsylvania

Application September 2, 1944, Serial No. 552,504

12 Claims. (Cl. 177—353)

1

My invention relates to remote control systems, and more particularly, to centralized traffic control systems for railroads of the code type, and to the line or communication circuits for such systems.

Systems of this character, as illustrated, for example, by the remote control system of my United States Patent No. 2,229,249, issued January 21, 1941, employ a single communication channel, comprising a pair of line wires extending from the office through each station in turn, over which control codes are transmitted at times in one direction, from the office to the stations, while at other times indication codes are transmitted over the same channel in the opposite direction from the stations to the office, each transmitter having access to the line only when it is free. To prevent interference in the event transmission is started in both directions at the same time, the first step of each control code delivered by the transmitter at the office is made relatively long in comparison with the first step of an indication code delivered by a transmitter at a field station. When the transmitter at the office and at a field station both start to transmit at the same time, the long element delivered by the office transmitter overrules the short element delivered by the station transmitter and suspends its operation until the code delivered by the office transmitter is completed, so that the two codes are transmitted successively without interference.

One object of my invention is the provision of a two-way repeater for use in systems of this character, for repeating the code signals from one line circuit or channel to another, in either direction, which functions in such a manner that the direction of transmission through the repeater is determined in accordance with the character of the first step of the received code.

A further object is the provision of a two-way repeater for use in remote control systems in which the central office operator is able to reverse the direction of transmission to break the transmission of a code from a remote station.

The purpose of my invention is to permit the line to be divided into sections energized by different sources of current so as to enable the distance between the office and the stations to be extended or to enable currents of different character to be used for energizing different sections, each section comprising a single channel arranged for two-way communication.

Another purpose of my invention is to enable a carrier current or radio channel to be interposed between the office and the line circuit con-

2

nected the stations in systems of the character described, which channel may if desired employ the same carrier frequency for the transmission of codes in both directions.

I shall describe several forms of apparatus embodying my invention, and shall then point out the novel features thereof in claims.

Referring to the accompanying drawings, Fig. 1 illustrates a normally energized series connected line circuit system similar to that shown in my Patent No. 2 229,249, but which as shown herein is divided into two sections comprising the line circuits 1 and 2, respectively, connected by a repeater station including the apparatus of my invention.

Fig. 2 shows an alternative arrangement comprising a multiple connected line circuit system like that shown in the system of my Patent No. 2,259,573, issued October 21, 1941, for remote control systems, which is likewise divided into two sections comprising the line circuits 3 and 4 connected by a repeater station as in Fig. 1. In this view the codes are transmitted over line 3 by carrier currents employing the same frequency for transmission in both directions.

Fig. 3 shows a modification of the system of Fig. 2 in which the line circuit system is divided into three sections, one of which employs carrier current apparatus as in Fig. 2 but uses radio in place of line wires. In this view the codes are transmitted between lines 3 and 4 as radio signals employing the same carrier frequency for transmission in both directions.

Fig. 4 shows a modification of the circuit for a selector reply 2F of the office coding unit of Patent No. 2,229,249, for use in connection with the repeater of my invention.

Similar reference characters refer to similar parts in each of the views.

The repeater apparatus shown herein is generally similar in the different views, and it will be described in detail in connection with Fig. 1. In this view it is to be understood that the terminal apparatus is that of the remote control system of my Patent No. 2,229,249, only those portions of the system which are directly associated with the line being shown herein. These portions include, at each field station, a master relay M, which when energized places the station apparatus in the transmitting condition, a transmitter relay T which operates periodically when relay M is energized to deliver its code to the line circuit, a line relay R responsive to the codes supplied to the line, and a coding unit CU comprising selecting apparatus for decoding the received codes and

which also controls the operation of the associated transmitter relay T. The apparatus at the control office is generally similar to that at the stations, comprising a master relay OM, a transmitter relay OT and a line relay OR governing a coding unit CU. In addition, a push button PB is provided by which relay OT may be steadily energized for the purpose of breaking the transmission of a code by a station as hereinafter described.

The repeater station apparatus as shown includes two line relays R1 and R2, controlled over the corresponding lines 1 and 2, each of which relays is adapted to repeat the operation of the other, as well as to repeat the operation of the corresponding transmitter relay OT or T. The repeater also includes three slow acting relays, comprising a timing relay L which serves like relay L1 of Patent No. 2,229,249 to distinguish between the short or long character of the first step of a code, and two bridging relays 1LB and 2LB by means of which the direction of transmission through the repeater is established and which serve to make the repeater operation dependent upon the continued operation of the line relays.

When the code system is in its normal at rest condition, as shown, the line relays OR and R1 are energized over line 1 and front contact b of relay R2, by battery B1 at the office, and the line relays R2 and R are energized over line 2, back contact c of relay 2LB and front contact b of relay R1, by another battery B2 at the repeater station, so that the repeater is normally in condition to transmit signals in either direction.

The transmission of a code is initiated either by energizing relay OM at the office to cause relay OT to periodically interrupt line 1, or by energizing relay M at a field station to cause the associated relay T to periodically interrupt line 2. In either case the opening of one line opens the other and relays R1 and R2 both release. Relay R1 then completes a circuit from one terminal B of a suitable local source of current at its back contact a over back contact a of relay 1LB through relay L to the other terminal C of the local source, so that relay L picks up, completing a circuit from terminal B over contacts a of relays R1 and L through relay 1LB to terminal C so that relay 1LB picks up. By closing its contact b, relay 1LB bridges contact b of relay R2, which serves when relay T is the initiating transmitter to advance the code in line 1 to the second step, provided relay OT is not operated, but when relay OT is the initiating transmitter the operation of relay 1LB serves to prevent transmission from line 2 to line 1, thereby establishing one-way transmission through the repeater from line 1 to line 2, as required for the transmission of control codes by the office relay OT.

When relay 1LB picks up, the opening of its back contact a deenergizes relay L.

If the code is one initiated by relay OT, the first step delivered to line 1 and repeated by relay R1 into line 2 is a long step, and relay L releases before the second step of the code is reached. Relay R1 responds to the code operation of relay OT and its contact b repeats the code received from line 1 into line 2 to operate relay R at each station in accordance with the operation of relay OT, the station coding units being conditioned by the first long step to receive the remainder of the control code as explained in the patent. At the repeater station relay 2LB remains released, and relay 1LB is held picked up due to its inter-

mittent energization over its own front contact a by relay R1 on the odd-numbered code steps, and releases when relay R1 becomes steadily energized at the end of the code, thereby restoring the repeater to its normal condition as shown.

If the code is an indication code initiated by relay T, and relay OT is not operated, the first code step as repeated into line 1 is terminated as soon as relay 1LB picks up and closes its front contact b, and consequently is somewhat shorter than the first step as measured by relay T. Relays R1 and OR become energized in response to the closing of contact b of relay 1LB, and the closing of front contact b of relay R1 connects battery B2 to line 2, so that relays R2 and R pick up when relay T releases to begin the second step of the code. Since the first step delivered by relay T is relatively short, in comparison with the first step of a control code, relay R2 picks up before relay L releases, and completes a circuit from terminal B over front contacts a of relays R1 and R2 and contact b of relay L through relay 2LB to terminal C. Relay 2LB therefore picks up on the second step of an indication code, whereupon its contact b opens the circuit shunting contact b of relay R2 to render relay R2 effective to control line 1, and the operation of contacts c and d of relay 2LB renders relay R1 ineffective to control line 2. Thus relay 2LB reverses the direction of transmission through the repeater to allow relay R2 to repeat the code received from line 2 into line 1 to operate relay OR at the office in accordance with the operation of relay T at the transmitting station. During the transmission of the indication code, relay 1LB is held picked up by intermittent energization on the odd-numbered steps as already described and relay 2LB is held picked up over its own front contact a and contact c of relay 1LB by intermittent energization on the even-numbered steps until relay R1 becomes steadily energized at the end of the code.

It is to be understood that in the system of the patent the initiation of a control code by relay OT is dependent upon the energization of the master relay OM, and that relay OM cannot become energized while an indication code is being received at the office. A control code thus takes precedence over an indication code initiated at about the same time only if relay OM picks up, otherwise the indication code is transmitted first. The direction of transmission is therefore determined by relay OM, that is to say, it is determined positively by the position of a single relay located at the office. It will be clear therefore that a single line repeater of the types ordinarily used in telegraph circuits would not be suitable for use in the system because in such repeaters the direction is determined by conditions at the repeater station.

Taking into account the time lag in the transmission of impulses over an electrically long line, it will be seen that in Fig. 1, after the station transmitter relay T operates to initiate a code, a short time may elapse before its effect becomes manifest at the office during which relays OM and OT may become energized. If relay OT becomes energized during the transmission of the first step of an indication code by relay T, relay R1 remains released holding line 2 open after relay T releases to cause relay R to respond to the long step and conditioning the station coding unit to receive the code delivered by relay OT, thereby preventing the further operation of relay T until the code delivered by relay OT is completed, pre-

cisely as if the office and station were controlled over the same physical line circuit as shown in the patent. It will be clear therefore that the direction of transmission under this condition is determined, not by the relative order of arrival of signals from two directions at the repeater station, but by the position of the office relay OM, the same as when a repeater is not used.

In systems of the character described it is the practice to provide apparatus at each field station which is controllable from the office by which the operator can disable the transmitter at a field station to prevent its continued operation in case of a fault. This is accomplished by holding the line relay R steadily released for a relatively long time interval by the operation of a push button PB located at the office. By reference to Fig. 1 it will be seen that if button PB is operated during the transmission of an indication code by relay T, relay OT will be steadily energized opening line 1 and causing the response of relay R1 to the code operation of relay R2 to cease, relay R1 remaining released and releasing relay 2LB, which places line 2 again under the control of relay R1, causing relay R to remain released, as required. It will be seen that since the operator is able to reverse the direction of transmission through the repeater at will the distant line 2 is at all times controllable from the office.

It may also happen in the normal operation of the system that two stations initiate indication codes at the same time. In this case the operation of relay M at the station nearer the office opens the portion of the line circuit leading to the more remote station so as to cause the two stations to transmit their codes successively without interference in the manner pointed out in the patent. In Fig. 1, some of the stations may be located in line 1 and others in line 2, and in this case if a station in line 1 and one in line 2 initiate codes at the same time relay M at the station in line 1 disconnects battery B1 from relay R1 and the effect at the repeater station is the same as when button PB is operated. It follows that the transmitter at the more remote station is disabled for the duration of the code transmitted by the nearer station with the same effect as if both stations were located in the same line section.

In the system of my patent the normal rate of operation is such that the short code steps have a duration of about .03 second, with the exception of the first step of an indication code which is about .05 second longer than the other short steps due to the operation of additional relays on that step. In the operation of the repeater as described this first step as received by the office relay OR is shorter than the first step delivered by relay T, as already pointed out, so that step two as received at the office is lengthened by a corresponding amount and the margin against the improper operation of the corresponding selecting relay when the second step transmitted by relay T is short is decreased. By reference to the patent it will be seen that but one selecting relay is involved, namely relay 2F. The circuit for this relay, as shown on Figs. 1 and 2 of the patent, and in a modified form in Fig. 4 of the present application includes contact e of a timing relay OL2 and wire 135, which circuit is closed upon the release of relay OL2 when the second step of an indication code is a long step. In Fig. 4 I have included a contact d of the repeating relay OLP of the patent, the release of which follows that of relay OL2, in the circuit for relay 2F, whereby the effect of the increased

length of the second step due to the repeater is overcome and the normal margin against operation restored. Relay 2F is also responsive to the second long step of a control code, but in that case its circuit already includes a contact b of relay OLP, shown in Fig. 1 of the patent and the modification shown herein in Fig. 4 consequently does not change the operation of relay 2F in response to a control code.

Referring now to Fig. 2, in this view the coding apparatus is connected in multiple with the line wires instead of in series as in Fig. 1, the line circuit comprising two sections 3 and 4 connected by a repeater which is similar to that of Fig. 1 except as modified to correspond with the change in line conditions. In Fig. 2 the terminal apparatus is correspondingly modified and it is to be understood that in this view and in Fig. 3 as well, the remote control system is arranged as shown in my United States Patent No. 2,259,573, issued October 21, 1941. The line circuits of Fig. 2 are normally deenergized and the code in pulses are in consequence opposite in phase to those of Fig. 1. Line 4, to which the field stations are connected, is energized on the odd-numbered code steps only by a battery B4 at the repeater station in the case of control codes or by a battery B4a at the transmitting station in the case of indication codes, and is deenergized on the even-numbered code steps. Line 3 as shown is energized by carrier currents, that is to say, by alternating current codes generated by electronic oscillators OSC at the office and repeater stations, with electronic amplifiers and a frequency selective filter HF interposed in the connections of the oscillators and of the line relays to the line. The repeater of my invention is of particular advantage in connection with carrier current transmission since it makes it possible to use currents of the same frequency for both directions of transmission and both oscillators are therefore preferably arranged to deliver currents of approximately the same frequency.

In Fig. 2 an impedance 10 is interposed in the connection of each line relay to the line, shunted by a back contact b of the associated transmitter relay in order to equalize the response of the line relay to the signals delivered by the associated transmitter and to the one at the distant end of the line as is desirable when the attenuation of the line signals is high, and a low pass filter LP is interposed in the connection of the stations to line 4 to render the line available for voice or carrier current communication.

Another difference in Fig. 2 is the provision of a repeating relay T4 for the line relay R4 which controls the delivery of the carrier current codes to line 3 at the repeater station, in order to confine these currents to the contacts of a single relay.

It is to be understood that the line circuit system of Fig. 2 may be a portion of a through line circuit with the sections connected by suitable band pass filters BP, and may include a plurality of sections similar to line 4 each having a repeater station at one end for repeating the codes over the intervening line between that section and the office by means of carrier currents as shown, each repeater and the associated office apparatus employing a different frequency.

It is also to be understood that a series connected line such as line 2 of Fig. 1 may replace the multiple connected line 3 in Fig. 2, or that radio communication may replace the transmission of carrier currents over line wires as illus-

trated by the line section 3, and that two or more repeaters may be interposed in the circuit connecting the office and stations of Fig. 1 or 2. The latter arrangement is illustrated more particularly in Fig. 3 in which a single frequency, two-way radio channel having the antennas A and A₁ as shown, provides a connection between two battery energized, multiple connected line circuits 3 and 4, Fig. 3 being in other respects similar to Fig. 2.

Considering the operation of Fig. 3, it will be seen that when relay OT is operated to deliver the first long impulse of a control code to line 3, relays R₃, T₃, L and 1LB respond at the first repeater station, relay T₃ transmitting a radio signal of corresponding duration from antenna A which is received over antenna A₁ at the second repeater station to energize the corresponding relays R_{3a}, L_a and 1LB_a, and the receiving relay R_{3a} supplies current from battery B₄ to line 4 over its front contact b to cause relay R at each field station to operate its coding unit CU in the manner already described in connection with Fig. 1.

When an indication code is initiated by the system of Fig. 3, relay T at the transmitting station picks up and operates the associated relay R and also operates relay R_{4a} at the second repeater station. Relay R_{4a} completes a circuit from terminal B at contact b of relay 1LB_a over its front contact b to operate the repeating relay T₄ which transmits a radio signal from antenna A₁. This is received by antenna A of the first repeater station to operate relay R₄. The carrier current delivered to antenna A₁ also operates relay R_{3a} locally. Relay R_{3a} by closing its front contacts a and b energizes relays L_a and 1LB_a of the second repeater station and supplies current from battery B₄ to line 4 to maintain relays R_{4a} and R energized. Contact b of relay R₄ at the first repeater station now closes to supply current from battery B_{3a} to line 3 to operate relays R₃ and the office line relay OR. Relay R₃ energizes relays T₃, L and 1LB at the first repeater station and relay T₃ delivers carrier current from the associated oscillator OSC to antenna A, which also holds relay R₄ energized.

At the second repeater station relay T₄ is released when relay 1LB_a picks up and opens its back contact b and relay R_{3a} is then held energized by the radio signal received over antenna A₁ from the first repeater station and continues to supply current from battery B₄ to line 4, under the control of relay R₃, as long as line 3 remains energized. When relay 1LB at the first repeater station picks up, its contact b disconnects battery B_{3a} from line 3, and its contact a connects relay R₃ directly across line 3, and if relay OT has not been operated relays OR and R₃ release, advancing the code supplied to line 3 to the second step, this occurring shortly before relay T releases to advance the code supplied to line 4 to the second step. Relay R₃ releases relay T₃, discontinuing the supply of carrier current to antenna A and releasing relay R₄. Since relays R₃ and R₄ are now both in the released position, relay 2LB picks up and the opening of its contact c prevents further operation of relay T₃, while the operation of contact b of relay 2LB to its upper position places line 3 under the control of contact b of relay R₄.

At the second repeating station relay R_{3a} releases when the carrier current received by antenna A₁ is discontinued, to disconnect battery B₄ from line 4, but relays R_{4a} and R are held

energized by current from battery B_{4a} and release when relay T advances to step two of the code. At the beginning of the second step of the code supplied to line 4, therefore, relays R and R_{4a} release, relay 2LB_a becoming energized. The operation of contact c of relay 2LB_a prevents further control of line 4 by relay R_{3a} and the operation of contact b of relay 2LB_a establishes relay T₄ as a repeater of relay T while relay 2LB, which is already energized, prevents further operation of relay T₃ and conditions relay R₃ to control relay OR through relay T₄ by relay T, as in Fig. 1 already described.

The operation of push button PB in Fig. 3 during the transmission of an indication code by relay T likewise has the same result as in Fig. 1. When button 2PB is operated, relay R₃ is steadily energized by battery B₃ or B_{3a} irrespective of the code operation of relay R₄, causing relay 2LB to release and relay T₃ to become steadily energized which in turn causes relay R_{3a} to be steadily energized to release relay 2LB_a and to then supply steady current to line 4 to terminate the operation of the transmitting coding unit as required.

Although I have herein shown and described only a few forms of apparatus embodying my invention, it is understood that various changes and modifications may be made therein within the scope of the appended claims without departing from the spirit and scope of my invention.

Having thus described my invention, what I claim is:

1. In a remote control system, an office and a station connected by a single communication channel, code transmitters at the office and station for delivering impulse codes to said channel, a two-way repeater interposed in said channel, a slow acting relay and a stick relay associated with said repeater, means for energizing said slow acting relay in response to the first element of a code received at said repeater station, means controlled by said slow acting relay for selectively energizing said stick relay in accordance with the relative length of said first element, means controlled by said stick relay for establishing one direction or the other for the transmission of the remainder of the code through the repeater in accordance with the position of said stick relay, and means responsive to said code for maintaining said stick relay picked up until said code is fully transmitted.

2. In a remote control system, an office and a station connected by a single communication channel, code transmitters at the office and station for delivering impulse codes to said channel, a two-way repeater interposed in said channel including two stick relays and a slow acting relay, means for energizing one stick relay and said slow acting relay in response to the first impulse of a code received at said repeater station, means controlled by said one stick relay for establishing one-way communication through said repeater, means controlled by said slow acting relay for selectively energizing the other stick relay in accordance with the relative length of said received impulse, means controlled by said other stick relay when energized for reversing the direction of communication through said repeater, and means controlled by the succeeding impulses of a code for maintaining one or both of said stick relays energized until such code is fully transmitted.

3. In a remote control system, an office and a

station, a first communication channel extending from the office to a distant point, a second communication channel extending from said distant point to said station, coding units at the office and station each including a transmitter for delivering impulse codes to the adjacent channel and a receiver responsive to codes supplied thereto at said distant point, means causing the first impulse of a code delivered by the office transmitter to be of one character and the first impulse of a code delivered by the station transmitter to be of a different character, a two-way repeater at said distant point normally effective to repeat an impulse received from either channel into the other, means responsive to the first impulse of a received code for rendering said repeater effective to repeat succeeding impulses from the first channel to the second channel only, a stick relay associated with said repeater, means for energizing said stick relay following the reception of the first impulse of a code at the repeater station provided such impulse is of the character delivered by said station transmitter, means controlled by said stick relay when energized for reversing said repeater so as to repeat the succeeding impulses of a code from the second channel to the first channel only, and means for maintaining said stick relay energized until such code is fully transmitted.

4. In a remote control system, an office and a station, a first communication channel extending from the office to a distant point, a second communication channel extending from said distant point to said station, coding units at the office and station each including a transmitter for delivering impulse codes to the adjacent channel and a receiver responsive to codes supplied thereto at said distant point, a two-way repeater at said distant point normally effective to repeat an impulse received from either channel into the other, means responsive to the first impulse of a code received over either channel for rendering said repeater effective to repeat impulses from the first channel to the second channel only, a stick relay associated with said repeater, means for energizing said stick relay following the reception of the first impulse of a code from said second channel provided no impulse is received from said first channel prior to the termination of said first impulse, means controlled by said stick relay when energized for reversing said repeater so as to repeat succeeding impulses received from the second channel to the first channel, and means for maintaining said stick relay energized only as long as the reception of such impulses continues.

5. In a remote control system, a two-way repeater connecting two communication circuits, comprising a line relay for each circuit, each such relay being responsive to code impulses received over its circuit from a distant transmitter and having a contact for repeating such impulses into the other communication circuit, means responsive to the first impulse of a code received from either of said circuits for locally terminating the corresponding impulse repeated into one of the two circuits before the received impulse is terminated, to thereby condition said repeater to repeat impulses in one direction only, from said one circuit into the other circuit, a stick relay, means for energizing said stick relay upon the termination of the first impulse of a code being received from the transmitter in said other circuit but only if no impulse is being received at the time from the transmitter in said one circuit, means controlled by said stick relay when energized for con-

ditioning said repeater to repeat the remaining impulses of the code received from said other circuit into said one circuit, and means for maintaining said stick relay energized only until such code is fully transmitted.

6. In a remote control system, a two-way repeater connecting two communication circuits, comprising a line relay for each circuit, each line relay being adapted to repeat the impulses received over the corresponding circuit into the circuit which controls the other, two slow acting relays controlled by one of said line relays and arranged to be energized successively by such line relay when the first impulse of a code is received from either direction, means controlled by the first slow acting relay for opening the circuit for the second slow acting relay to effect its release during the first impulse received but only if such impulse is relatively long, means controlled by said first slow acting relay when energized for terminating the control of one of said line circuits by the line relay for the other to establish one-way transmission through said repeater, a stick relay controlled by the second slow acting relay, means effective if the first impulse received is terminated before said second slow acting relay releases for energizing said stick relay, and means controlled by said stick relay when energized for reversing the direction of transmission through said repeater.

7. In a remote control system, a two-way repeater connecting two communication circuits including a line relay for each circuit, each responsive to code impulses received over the corresponding circuit and normally adapted to repeat such impulses into the other circuit, two stick relays controlled by said line relays, a pick-up circuit for one stick relay closed when the first impulse of a code is received over either circuit, means effective upon the energization of said one stick relay for rendering the line relay controlled from said distant station ineffective to control the circuit extending to the office thereby establishing one-way communication from the office to the distant station through said repeater, a pick-up circuit for the other stick relay closed only if no impulse is received from the office during the reception of the first impulse of a code from the distant station, and means effective when said second stick relay becomes energized for rendering the line relay controlled from said distant station effective to again control the circuit extending to the office and for rendering the other line relay ineffective to control the other circuit, and a holding circuit for each stick relay including its own front contact and a contact closed intermittently during the code operation of said line relays.

8. In a remote control system, a repeater including two line relays, a code transmitter at a control office for supplying code impulses to a first communication circuit extending to said repeater for controlling one of said line relays, a code transmitter at a distant station for supplying code impulses to a second communication circuit extending to said repeater for controlling the other line relay, means including contacts of said one line relay for repeating code impulses received from the office into said second circuit, means controlled by the other line relay in response to the first impulse of a code received from said station for locally generating an impulse of relatively brief duration and for supplying such impulse to said first circuit, and means effective only if no impulse is received from the office dur-

ing the reception by said repeater of the first impulse of a code received from said station for rendering the line relay for said second circuit effective to repeat the succeeding impulses of such code into said first circuit.

9. In a remote control system, a repeater including two line relays, a code transmitter at a control office for supplying code impulses including a relatively long first impulse to a first communication channel extending to said repeater for controlling one of said line relays, a code transmitter at a distant station for supplying code impulses including a relatively short first impulse to a second communication channel extending to said repeater for controlling the other line relay, code receivers at the office and station, means including contacts of said one line relay for repeating code impulses into said second channel to which the other line relay and the station receiver are responsive, means including contacts of the other line relay operated in response to the short first impulse of a code received from the station for supplying a locally generated impulse of relatively brief duration to said first channel to which said one line relay and the office receiver are responsive, means selectively responsive to the long first impulse of a code received from the office for rendering the line relay controlled over said second channel ineffective to supply impulses to said first channel, and means effective upon the termination of the short first impulse of a code received from the station provided no impulse is received from the office during the reception of such impulse for rendering the contacts of the other line relay effective to repeat the succeeding impulses of such code into said first channel and for preventing said one line relay from repeating such impulses back into said second channel.

10. In a remote control system, a first and a second communication circuit connected by a repeater normally responsive to a code impulse received over either circuit for supplying an impulse to the other circuit, means in said repeater for terminating the impulse supplied to one circuit prior to the termination of the controlling impulse received from the other circuit, said repeater remaining effective to repeat succeeding code impulses in the opposing direction only from said one circuit to said other circuit, and means effective if no impulse is received from said one circuit during the reception of said impulse from

the other circuit for reversing said direction to render the repeater effective to repeat succeeding impulses from said other circuit to said one circuit only.

- 5 11. In a remote control system, an office and a station connected by a single communication channel, code transmitters at the office and station for delivering impulse codes to said channel, interference preventing means at the office 10 for determining the direction of code transmission over said channel in the event the transmission of codes is initiated at the office and station at approximately the same time, a two-way repeater interposed in said channel and normally effective to repeat to said station a code impulse received from the office and to transmit an impulse of brief duration to said office in response to an impulse received from said station, said repeater then becoming effective to repeat impulses in one direction from the office to the station only, and means effective if no impulse is received from the office in response to the operation of said interference preventing means during the reception of an impulse from said station 15 for reversing the direction of said repeater to render it effective to repeat impulses from the station to the office only so long as the transmission of such impulses continues.
- 20 12. In a remote control system, an office and a station connected by a single communication channel, code transmitters at the office and station for delivering impulse codes to said channel, a two-way repeater interposed in said channel and normally effective to repeat to said station a code impulse received from the office and to transmit an impulse of brief duration to said office in response to an impulse received from said station, said repeater then becoming effective to repeat impulses in one direction from the office to the station only, and means responsive to the first impulse of a code received from the station 25 for reversing the direction of said repeater to render it effective to repeat impulses from the station to the office only, said means being responsive to prolonged impulse received from the office during the transmission of any of said impulses including said first impulse for restoring said repeater to its original direction in which it is effective to repeat impulses from the office to the station only.

LLOYD V. LEWIS.
